UNITED STATES PATENT OFFICE

2,362,685

ROCKER

John Damsted, Sudbury, Ontario, Canada

Application August 27, 1943, Serial No. 500,261

1 Claim. (Cl. 155—69)

This invention consists of a rocker, being an amusement device for children or adults. Its primary object being to provide such a device that will accommodate one or more children or adults and that is safe and easily moved from place to place.

Another object of the invention is to devise and construct a rocker having a plurality of seats to accommodate several people and may be provided with side doors to permit older people to get into the structure.

With these and other objects in view that may appear while the description proceeds the invention consists in the novel construction and arrangements of parts as hereinafter more specifically set forth, claimed and shown in the accompanying drawings forming part of this application and in which:

Fig. 1 is a plan view of my invention.

Fig. 2 is a side elevation of the structure.

Fig. 3 is a sectional elevation of the device.

Fig. 4 is a sectional elevation showing a modification of the construction.

Fig. 5 is an end elevation.

Fig. 6 is a cross sectional elevation.

Fig. 7 is a side elevation showing a modification having doors constructed in the side thereof.

Referring more in detail to the drawings in which similar reference characters designate corresponding parts throughout the several views it will be seen the invention consists of two side frame members 10, the lower edges of which are curved to form rockers 11. End members 12, are attached thereto form a rectangular frame structure.

End seats 13, and 14, and a central seat 15, with a back rest 16, are provided and attached to the side frame members 10. Foot boards 17, are also attached to the said side frame members. The seats and foot boards may be also supported on cleats 18, attached to the side members.

In the modification shown in Fig. 4, foot

guard boards 19, are provided to prevent children's feet or legs being extended through the spaces and getting under the rockers thereby providing safety means.

5 In Fig. 7, one side frame member 10, is provided with doors 20, mounted on hinges 21, and having lock handles 22, by means of which the doors are secured in the closed position.

From the foregoing it will be seen I have provided an amusement device made almost entirely of wood and one that is inexpensive and simple to construct.

10 It is believed that the construction and advantages of the device may be apparent from the foregoing paragraphs taken in conjunction with the accompanying drawings without further detailed description.

15 While the preferred embodiment of the invention has been disclosed it is understood that minor changes in the detail of construction and arrangement of cooperating parts may be resorted to within the scope of what is claimed without departing from the spirit of the invention.

I claim:

20 A rocker comprising a rectangular frame composed of spaced parallel side members and end members, said side members having their lower edges curved longitudinally forming rockers, end seats extending transversely of the frame adjacent the upper edges of the side members, the end members extending upwardly to form back rests for the end seats, an intermediate seat extending transversely of the frame on a horizontal plane lower than the plane of the end seats, a back rest for the intermediate seat, foot boards between the end and intermediate seats below the horizontal planes of said seats, risers between the foot boards and seats, and doors in one of the side members of the frame to permit access to the
